(57) **CLAIM**

The ornamental design for a beer growler, as shown and described.

DESCRIPTION

1. Beer growler

1.1 is a front perspective view of the beer growler.

1.2 is a front view thereof where the back view is a mirror image.

1.3 is a left view thereof.

1.4 is a right view thereof.

1.5 is a top view thereof.

1.6 is a bottom view thereof.

The fine lines on the drawings indicate the flat surface or curved surface; this is a design for a beer growler made of synthetic resin and metal.

The dash-dot broken line in 1.6 defines the bounds of the claimed design and forms no part thereof.
